UNITED STATES PATENT OFFICE

104,741

DESIGN FOR A MONUMENT

Cloyd K. Grubbs, Muncie, Ind.

Application August 10, 1936, Serial No. 64,314

Term of patent 14 years

To all whom it may concern:

Be it known that I, Cloyd K. Grubbs, a citizen of the United States and a resident of Muncie, in the county of Delaware and State of Indiana, have invented a new, original, and ornamental Design for a Monument, of which the following is a specification, reference being had to the accompanying drawing, forming a part thereof, and wherein Figure 1 is a front view, Figure 2 is an end view, and Figure 3 is a top plan view of a monument showing my new design.

I claim:

The ornamental design for a monument, substantially as shown.

CLOYD K. GRUBBS.
